CLOTH ROLL DRIVE

Walter J. Budzyna, East Douglas, Mass., assignor
to Draper Corporation, Hopedale, Mass., a cor-
poration of Maine

Application September 22, 1937, Serial No. 165,109

3 Claims. (Cl. 192—79)

The present invention pertains to loom take-ups, and more particularly to the cloth roll drive thereof.

In loom take-ups of the type to which my invention applies, the cloth is wound onto a cloth roll which is driven from a rotating driving member by friction shoes engaging the driving member. The cloth roll has a gudgeon on which the driving member is loosely mounted. The friction shoes have positive driving connection with the gudgeon and spring means urge the shoes into engagement with the driving member. Manual rotation of the cloth roll, for removing the cloth therefrom or for other purposes, cannot be conveniently accomplished unless the cloth roll is released or freed from the driving member.

Loom take-ups of the type above mentioned, as heretofore constructed commercially, were so arranged that the cloth roll could be freed from the driving member only by unscrewing adjusting nuts which were provided for adjusting the tension of the aforesaid spring means. The unscrewing of such adjusting nuts is a time-consuming operation, and is further objectionable in that it destroys the adjustment and thus provides an opportunity for improper readjustment of the tension on the friction shoes. Several attempts have been made to overcome this objectionable feature of the commercial form of cloth roll drive, but the constructions proposed heretofore have not been satisfactory for various reasons, which need not be discussed.

A principal object of the present invention is to provide, in a cloth roll drive for loom take-ups, a cloth roll having a gudgeon, a rotating driving member on the gudgeon, friction shoes connected to the gudgeon, and spring means for urging the shoes into engagement with the driving member as aforesaid, and a novel manually operable cam means carried by the shoes and operable to release the shoes from the driving member against the action of said spring means, whereby any adjusting means provided for the spring means need not be disturbed when it is desired to free the cloth roll for rotation independent of the driving member.

The foregoing and other objects of the invention are accomplished in the construction illustrated on the accompanying drawing, of which:

Fig. 1 is a perspective view of part of a loom having the preferred embodiment of my invention applied thereto;

Fig. 2 is a detail view, to a larger scale, of certain parts shown on Fig. 1;

Fig. 3 is a view in cross-section taken approxi-

mately on line 3—3 of Fig. 2, but with the releasing cam turned around from its Fig. 2 position so as to appear in full lines; and

Fig. 4 is a detail of the releasing cam and certain contiguous parts.

The drawing shows parts of a loom frame, including the front part of a right hand loom side 1, a breast beam 2, a girt 3 and a vertical stand 4 which is supported by the breast beam and girt. A take-up roll or feed roll 5 is journaled in suitable bearings supported by stands such as the stand 4. The take-up roll 5 is positively revolved at a uniform speed, to feed the cloth forwardly in the loom, by any suitable usual means not shown. The cloth C which is thus fed by the take-up roll is found onto a roll 6 commonly called a cloth roll. The cloth roll must revolve at a comparatively faster rate when substantially empty than when nearly full, the rate progressively decreasing as the diameter of the cloth supply increases.

The cloth roll 6 has a fixed gudgeon 7 projecting from the end thereof, which gudgeon may be journaled in a bearing 8 supported by the stand 4. The varying speed of the cloth roll requires that the roll be driven by a friction or slipping drive and such drive is commonly effected from a rotating driving member loosely mounted on the cloth roll gudgeon. The drawing shows at 9 a conventional form of such driving member, which is loosely mounted on the gudgeon 7. The driving member 9 includes a friction drum 10 and a sprocket 11 formed integrally with the drum. A chain 12 passes around the sprocket 11 and around a sprocket 13 which revolves with the take-up roll 5, whereby the member 9 is revolved by the take-up roll. The aforesaid slipping drive is provided by friction means engaging and driven by the drum 10.

In the embodiment shown, the friction element 40 driven by the drum 10 comprises radially acting shoes 14 and 15 which are pivoted together by means of a pivot pin 16. These shoes are curved to fit the external periphery of the drum 10 so that they constitute a friction band which is supported on the drum. The shoes 14 and 15 have positive driving connection with the gudgeon 7, as by means of a driven part 17. The part 17 consists of an arm which is fixed to the gudgeon 7 by set screws 18 and the free end 19 of which is connected to the shoe 14 by being bent over and positioned in a socket 20 in the shoe.

Spring means for urging the shoes into frictional engagement with the drum 10 may include a coiled compression spring 21 and a bolt 22. The

free ends 23 and 24 of the shoes 14 and 15 are turned outwardly approximately radially and the bolt 22 passes loosely through holes in such ends. A head 25 on one end of the bolt engages the end 23. The spring 21 is positioned on the end of the bolt opposite the head 25 and is compressed between adjusting nuts 26 and the end 24 of shoe 15. The spring thus acts on the bolt 22 and on the shoe 15 to contract the shoes, i. e., to urge the shoes together, into frictional engagement with the drum 10. When the spring so acts, the cloth roll is revolved by the driving member 9 but the friction shoes may slip on the drum so that the cloth roll is revolved only just fast enough to wind up the cloth C that is fed by the take-up roll 5.

It will be apparent that whenever the cloth is to be removed from the cloth roll, or the roll is to be manually rotated for any other reason, such rotation must be effected against the frictional resistance of the shoes 14 and 15 on drum 10 or the shoes must be released from the drum. The former is obviously impractical and to release the shoes by unscrewing the adjusting nuts 26 would be objectionable for reasons above stated. I have accordingly provided manually operable cam means for expanding or releasing the shoes from driving engagement with the drum against the action of the spring 21, without disturbing the adjusting nuts 26.

The preferred embodiment of the aforesaid cam means comprises a cam 27 which is carried by the friction shoes and which is manually rotatable into engagement with one of the shoes. To this end, the cam may be gripped between a nut 28 and a knurled nut 29 which are threaded onto the bolt 22. These nuts may be loosened and then turned to adjust the cam longitudinally of the bolt but when tightened the nuts firmly hold the cam against any movement relative to the bolt.

In the normal operation of the loom, the cam 27 will be positioned as shown on the drawing, that is, it will be out of engagement with the friction shoes. When the loom is stopped and the cloth roll is to be manually rotated, the nut 29 may be grasped and the nut, bolt 22 and the cam 27 manually rotated in either direction to bring the cam into engagement with the end 24 of shoe 15. At such time the cam rides up the inclined edge 30 of end 24 and pulls the bolt 22 endwise against the action of spring 26. This expands or releases the shoes from the drum 10 and thus frees the cloth roll so that it may be

manually rotated independently of the driving member 9.

Having fully disclosed the preferred embodiment of my invention, I claim:

1. In a cloth roll drive for loom take-ups, the combination of a cloth roll having a gudgeon, a driving member comprising a revolving friction drum loosely mounted on said gudgeon, a pair of friction shoes having fixed driving connection with said gudgeon, said shoes being pivoted together and being curved to fit the external periphery of said drum, a bolt passing through the free ends of said shoes, spring means acting on the free ends of said shoes to urge the shoes into frictional engagement with said drum, and a cam mounted on said bolt, said cam being manually rotatable into engagement with the free end of one of said shoes to release the shoes from said drum against the action of said spring means.

2. In a cloth roll drive for loom take-ups, the combination of a cloth roll having a gudgeon, a driving member comprising a revolving friction drum loosely mounted on said gudgeon, a pair of friction shoes having fixed driving connection with said gudgeon, said shoes being pivoted together and being curved to fit the external periphery of said drum, a bolt passing through the free ends of said shoes, a spring acting on said bolt and on one of said shoes to urge both shoes into frictional engagement with said drum, and a cam mounted on said bolt between the free ends of said shoes, said cam being manually rotatable into engagement with one of said shoes to release the shoes from said drum against the action of said spring.

3. In a manually releasable cloth roll drive for loom take-ups, the combination of a driving member comprising a revolving friction drum, a driven element comprising a pair of friction shoes pivoted together and curved to fit the external periphery of said drum, a bolt passing through the free ends of said shoes, said bolt having a head engaging one of said shoes, a compression spring on the other end of said bolt, said spring acting on said bolt and on one of said shoes to urge both shoes into frictional engagement with said drum, and a cam fixed on said bolt between the free ends of said shoes, said cam being manually rotatable into engagement with one of said shoes to pull said bolt endwise against the action of said spring to thereby release the shoes from said drum.

WALTER J. BUDZYNA.
